UNITED STATES PATENT OFFICE.

WARREN STEPHEN WILLIAMS, OF ZANESVILLE, OHIO.

PENCIL.

1,274,485.

Specification of Letters Patent. Patented Aug. 6, 1918.

Application filed December 6, 1916. Serial No. 135,427.

To all whom it may concern:

Be it known that I, WARREN S. WILLIAMS, a citizen of the United States, residing at Zanesville, in the county of Muskingum and State of Ohio, have invented a new and useful Pencil, of which the following is a specification.

This invention relates to pencils of the type in which the lead or crayon is fed by mechanical devices.

An object of the invention is to provide a construction in which the cross-sectional form of the outer casing, as well as the cross-sectional form of the crayon or lead used is immaterial; that is to say, my invention when embodied in concrete form will comprise mechanism which may be actuated to feed the lead or crayon irrespective of the cross-sectional form of the outer casing or of the crayon.

Another object of the invention is to provide a construction which will prevent the operating parts of the pencil from falling out when inverted, or from being pulled out when the end cover is removed for exposing the eraser or when the pencil is removed from the pocket.

Another object of the invention is to provide a nozzle or tip having centering devices, which will coöperate with the casing or with a lead holder and guide on the plunger to properly guide the lead or crayon.

A further object of the invention is to provide a construction which will be compact, simple and durable, and in which a magazine may be located in the actuating bolt, whereby access may be had to surplus leads or crayons without dislodging or dislocating the operating parts.

The means by which the above objects and others are obtained are briefly described as follows: The pencil herein illustrated comprises an outer casing which may be of any geometrical cross-section, but which is preferably of uniform cross-section from end to end, being devoid of screw-threads, and the like. Located within the casing is a longitudinally movable nut, which is non-rotatable relatively to the casing. Longitudinal movement is given to this nut by means of a rotatable bolt, which is held against longitudinal movement by a suitable bearing, or by a suitable connection with the outer casing. This bolt is centrally arranged and is provided with threads which engage the

threads of the nut. Rotation of the bolt will cause the nut to move longitudinally of the casing. The tip or nozzle of my pencil is provided with suitable centering devices with which the plunger, which is connected to the nut, coöperates.

In the particular construction herein illustrated, the rotating bolt for actuating the nut and plunger is hollow or recessed to provide a suitable magazine for surplus crayons and leads. The end of the bolt is closed by means of a plug, which may support an eraser. Several forms of the invention have been illustrated, and for a fuller disclosure of the same, reference is made to the accompanying drawings, in which:—

Figure 1 is a side view of one form of my pencil, on a reduced scale.

Fig. 2 is a longitudinal sectional view through the same.

Fig. 3 is a cross-section, taken on the line 3—3 of Fig. 2.

Fig. 4 is a cross-section, taken on the line 4—4 of Fig. 2.

Fig. 5 is an end view, looking toward the left of Fig. 2.

Figs. 6 and 7 are slightly modified forms which illustrate several cross-sectional shapes or forms that the bore or lead may have.

Fig. 8 is a sectional view of a cylindrical form of my pencil.

Fig. 9 is a cross-section, on the line 9—9 of Fig. 8.

Fig. 10 is a view illustrating a slightly modified form of nut which may be used in connection with my invention.

Fig. 11 is a sectional view thereof on the line 11—11 of Fig. 10.

Fig. 12 is a sectional view of a slightly modified form of the nut illustrated in Figs. 10 and 11.

Fig. 13 is a sectional view through a cylindrical form of nut, showing the lugs thereon by which it is connected to the outer casing to prevent the relative rotation of the casing and nut.

Figs. 14 to 18 illustrate other cross-sectional forms which the nut of my invention may have.

Fig. 19 is a sectional view, illustrating a modified form of bearing and cap for the top of the pencil.

Figs. 20 and 21 illustrate two forms of the

invention, in which the bearing for supporting the rotatable bolt is omitted.

Figs. 22 and 23 are modified forms of the devices illustrated in Figs. 20 and 21, and 5 in which lugs are provided to prevent the downward movement of the rotatable bolt toward the tip of the pencil.

Fig. 24 is a further modified form illustrating the way in which the head of the bolt 10 may be mounted within the pencil, and showing how a key connection may be made between the cap and the head of the bolt when the parts are cylindrical.

Fig. 25 is a cross-section on the line 25—25 15 of Fig. 24.

Figs. 2 to 25 inclusive are on an enlarged scale.

Referring to Figs. 1 to 5, I have therein illustrated my invention as applied to a pencil having a hexagonal cross-section. The outer casing is indicated at 1 and is provided with a tapering nozzle or portion 2. Located within this tapering portion of the casing is a centering and clamping member 25 3, provided with an inner funnel-shaped portion or centering device 4 adapted to properly direct the lead or crayon to the center thereof and into the longitudinally extending tapered portion 5 having a passage 5^a. The portion 5 surrounding the passage 5^a is split as indicated at 6 to allow the adjustment of the same to clamp the lead. For adjusting this portion of the clamping and centering member 3, the end 35 of the pencil is provided with a tip 7 having a screw-threaded tapered recess 8 which encircles and is attached to the portion 5. Other means besides the screw-threads may be used for adjusting the tip upon the portion 5. By adjusting the tip over the clamping portion 5, the passage therethrough is contracted to clutch the lead or crayon. The tip 7 is not loosened every time the lead is to be propelled forwardly or rearwardly. 45 The clamping device is only intended to be used when the lead is of such a small cross section that it tends to fall out. The adjustment should be sufficient to prevent this without interfering with the normal feeding 50 of the lead. In the construction here shown, when it is necessary to adjust the clamping device, where the lead is of a cross section, as shown, for instance, in Figs. 6 and 7, the same must be first removed to prevent the 55 breaking thereof. When the cross section is round, removal is not necessary. This tip is provided with a passage 9, which is in alignment with the passage 5^a. As indicated in Fig. 5, this passage is cylindrical, although 60 other shapes may be given to the same as is indicated at 9^a, Fig. 6, or 9^b, Fig. 7. The passages 9, 9^a and 9^b may be roughened, as indicated at 10, Fig. 2, to better hold the lead or crayon. The tip 7 of the pencil converges and merges with the portion 2 to

make a tapered end of symmetrical form, as is clearly shown in the drawings.

It will be noticed by referring to Fig. 4, that the casing 1 is hexagonal in cross-section, and slidably fitted within this casing 70 is an elongated nut 11 closed at the end adjacent the tip, and which corresponds in cross-section to the cross-section of the casing, whereby it is rendered non-rotatable and is free to slide longitudinally thereof. The 75 nut is provided with a cylindrical screw-threaded bore 12 adapted to receive the bolt whereby the nut is actuated back and forth.

Mounted upon the end of the casing 1 remote from the tip is a bearing 13, which projects and fits inside of the casing and is normally fixed against longitudinal movement by any suitable means, and as here shown, by a tight frictional engagement. The bearing 13 is provided with a flange 13^a, 85 which projects over the end of the casing, whereby movement of the bearing toward the tip is positively prevented, and it is held securely in place. This bearing is provided with a cylindrical central opening 14, in 90 which is rotatably mounted the screw-threaded bolt 15. This bolt is provided with an annular ring 16 fixed thereto inwardly from or below the bearing, which prevents the movement of the bolt outwardly or upwardly, while downward or inward movement of the bolt is prevented by means of the enlarged head 17, which extends above or outside the flanged portion 13^a of the bearing. 100

Where a cylindrical casing is used, as in Fig. 8, the bushing may be removably secured to the casing by a screw-threaded engagement, substantially as there shown.

The threaded portions of the nut and bolt 105 engage, and the rotation of the bolt causes the nut to move back and forth in the casing without rotation. In the embodiment of the invention here shown, the bolt is made hollow and provided with an inner chamber 110 18 adapted to receive surplus crayons or leads. The head 17 of the bolt and the top or outer end of the receptacle 18 is provided with an inclosing cup-shaped cover or plug 19 having mounted therein an eraser 20. 115 The head of the bolt is inclosed by means of an actuating cap 21, which is preferably held non-rotatable relatively thereto, so that the rotation of the cap when engaged by the fingers will cause the rotation of the bolt. 120

As illustrated in Fig. 3, the cross-sectional shape of the cap corresponds to the cross-sectional shape of the head over which it passes, and, in the present instance, these parts are angular, whereby the relative rotation is prevented.

There has also been provided a suitable clip 22, which engages one of the flat portions 23 of the pencil, as is clearly shown in Fig. 1. 130

The nut 11 is provided with a plunger 24, which is fixed to the same, and of course, is non-rotatable. This plunger is adapted to project into the passageways 5^a and 9 to feed the lead or crayon forwardly, and to finally eject it. The plunger should correspond, in cross-section, to the cross-section of the passageways in order to work properly.

10 The outer end 25 of the plunger is slightly enlarged, and loosely mounted thereupon is a cylindrical lead holder 26 to hold the lead in alignment with the plunger. This lead holder is provided with a longitudinal bore 15 or opening 27 having one end reduced in diameter, so that it will be impossible to pull the same off the plunger. However, sliding movement of the holder upon the plunger from the end toward the nut is possible. In 20 order to place the lead within the holder, the bearing, bolt and nut are withdrawn from the casing by exerting a hard pull upon the bearing to overcome the frictional resistance thereof. The holder is now drawn to the 25 end of the plunger, as shown in Fig. 2, and the lead inserted through the opening thereof in alignment with the plunger. The parts are now reinserted within the casing and occupy the position shown in Fig. 2. It 30 will be seen, (Fig. 2) that as the bolt is now rotated, the plunger with the holder 26 and the crayon or lead will be moved toward the tip. As the movement continues, the holder will engage the funnel portion 4 of the combined centering and clamping member 3, and continued movement of the holder will then be rendered impossible, but the plunger 24 will still continue to move forwardly 35 pushing the lead with it and guided by the holder, until finally the lead is entirely used up or ejected. When in its extreme forward position, the end of the plunger will be at the end of the tip, and further movement of the same will be prevented by reason of the 40 fact that the nut will engage the portion 4 or holder 26. This positive stop prevents the stripping of the threads on the bolt and nut and the jamming of the plunger in the centering device.

45 Referring to Figs. 2, 4, 8 and 9, I have there shown an arrangement by which the length of the lead or crayon remaining in the passageways may be known. For this purpose, the nut is provided with a longitudinal slot 29 exposing the bolt. The casing 1 is also provided with a slot 30 extending lengthwise of the bolt and overlapping the slot 29. In the construction of my pencils, the threaded portion of the bolt will be of a 50 length which is substantially equal to the length of the lead or crayon used.

55 In Fig. 8, the end of the bolt is indicated at 31, while the head of the nut, which is moved longitudinally by the bolt is indicated at 32. As the bolt is rotated to feed

the lead or crayon, it will be noticed that the portion 32 of the nut will approach the end of the bolt 31, and the distance between this portion and the end is the index of the length of the lead or crayon in the passageways. 70

In order to prevent the rotation of the nut within the casing of the construction shown in Figs. 8 and 9, I have provided this form with tongues 33, as is clearly shown in Figs. 75 9 and 13, which project into suitable grooves of the casing whereby the rotation of the nut relatively to the casing is prevented.

The elongated solid construction of nut illustrated in Figs. 2 and 8 may be modified, 80 as shown in Figs. 10 and 11. Instead of having an elongated portion, as above described, the nut may comprise a short annular ring 34, which is threaded to engage the bolt, and longitudinally extending bars 35, 85 provided with a cross-piece 36 at the ends thereof remote from the annular portion 34. To this cross-piece is fixed the plunger 24, which is of the same construction as that disclosed in Fig. 2. The bars 35 may be square 90 as is clearly shown in Fig. 11, which is a cross-sectional view of Fig. 10, or they may be round, as shown in Fig. 12 and indicated at 35^a.

In Figs. 14 to 18, I have illustrated a few 95 of the many cross-sectional forms that my nut may have. The whole idea is to prevent the rotation of the nut within the casing. The casing will correspond in cross-section to the nut, whereby the relative rotation of 100 the casing and nut is prevented. Each of the nuts, as will be clearly seen from an inspection of these last-mentioned figures, are provided with a cylindrical threaded opening into which projects the bolt, as shown in 105 Fig. 2.

In Fig. 19, I have illustrated a modified form of bearing and head for the bolt, in which the main casing is indicated at 40, and the bearing at 41, the latter having a 110 tight fit with the interior of the casing, and being provided with a central opening 42 at its top or outer end. Located above or outside the bearing is a head 43, which has connected to it, below the bearing, a fork 44, 115 by means of a cylindrical neck 45, rotatably mounted within the opening of the bearing 41. The bolt 46 is pivotally connected to the fork by means of a cross pin 47. A suitable eraser 48 is mounted in the head 43, and the whole is covered by means of a cap 49 mounted upon the head non-rotatably. 120

When access is desired to the surplus leads or crayons located in the magazine of the bolt 46, the whole structure is pulled out of 125 the casing and the leads or crayons may be easily removed by swinging the head and bearing around the pin or axis 47.

In Fig. 20, I have illustrated a form in which the extra bearing, as illustrated in 130

Fig. 2, has been omitted. In the modification here shown, the casing is indicated at 50, and the hollow bolt 51 is provided with a head 52, which closely fits the interior of 5 the casing. A plug 53 is removably mounted on the end of the bolt, closing the chamber within the bolt, and within this plug is located the eraser 54. A suitable cover 55 is also provided, which fits over the head of 10 the bolt and is non-rotatable thereon.

The close engagement between the head and casing of the construction in Fig. 20 is normally sufficient to keep the head from falling out. This engagement, however, is 15 not sufficient to prevent the rotation of the head when actuated.

In Fig. 21, I have shown a still further modified form in which the head is shown 20 separate from the body of the bolt. This head, in the present instance, is indicated at 56, and is rotatably mounted in the end of the casing. The hollow bolt 57 is screw-threaded into a recess 58, located in the opposite end of the head. A suitable cover or 25 cap 60 is non-rotatably mounted upon the head 56. In the construction shown in Figs. 20 and 21, however, it should be noticed that the bearings have been omitted and that the 30 constructions here shown are in connection with cylindrical casings.

In Fig. 22, which is a construction similar to that shown in Fig. 20, I have provided suitable flanges 61, which overlap the end of the casing, whereby movement of the bolt 35 toward the tip will be prevented. The construction in other respects is the same.

Fig. 23, which is similar to the construction shown in Fig. 21, is likewise provided with a flange 61^a for preventing the movement of the bolt toward the tip and providing a suitable bearing surface for the same.

In Figs. 24 and 25, I have illustrated a further form of my invention, in which the casing is indicated at 62. The bearing 63, which is similar to the bearing disclosed in Fig. 19, is provided with an opening 64. Mounted below this opening is a portion 65 which is connected by means of the neck 66 45 rotatably mounted within the opening 64 to a cup-shaped cylindrical portion 67, in which is mounted the eraser 68. The bolt is screw-threaded in the lower end of the member 65. In order to prevent the rotation of the cap 69, around the cylindrical portion 67, I have provided the same with inwardly 50 extending ribs 70, which engage suitable longitudinally extending grooves upon the portion 67 to prevent the rotation of the cap 60 relatively thereto.

In order to rotate the bolt to actuate the plunger, whenever the cap is in place, it will be necessary to rotate the cap, and for this reason the cap, in each instance, is mounted 65 upon the head of the bolt non-rotatably.

Various devices may be utilized for this purpose, and I have herein described several of such devices for so mounting the cap upon the bolt.

It will be seen from the forms described, 70 that I have provided a very simple mechanism of few parts, in which the actuating nut is non-rotatable in the casing, whereby the casing may be of any cross-sectional shape. The centering nozzle is arranged 75 with reference to the plunger so that the lead or crayon may be easily inserted into the same and properly directed and fed, so that breaking of the lead or crayon will not take place. The rotatable bolt is suitably 80 journaled in bearings or otherwise at one end of the outer casing and projects inwardly a sufficient distance to advance the nut the necessary distance to feed the crayon or lead.

In the construction shown in Fig. 2, it is not always necessary to center the lead by means of the element 25, but the lead may be allowed to slide down the side of the casing, when the operating parts have been 90 removed, into the passageway 5^a. The plunger, nut and bolt may then be reinserted and the plunger forced forwardly to cause the lead to feed out through the end of the pencil. This manner of inserting the lead, how- 95 ever, would not be possible in constructions in which the outer casing is threaded, as such would tend to displace the lead and to break the same. In my construction the outer casing, as far as longitudinal direction is concerned, is smooth and devoid of 100 screw-threads, the nut being actuated centrally by means of the threaded bolt, which was described above.

While I have shown and described several modifications of my invention, it is to be understood that I do not desire to be limited to the details of construction herein shown and described, for obvious modifications and changes will be apparent to any- 110 one skilled in the art.

What is claimed is:—

1. In a pencil, a casing having a tip and smooth internal walls, a nut longitudinally movable within said casing and guided by 115 the walls thereof, the interior of said casing and the exterior of said nut being polygonal in shape to prevent rotation of said nut as it is moved along the casing, a plunger connected to said nut to move with the 120 same, a screw-threaded elongated bolt rotatably mounted within and engaging said nut and of greater length than the latter, said bolt being hollow throughout and closed at all points except the outer end thereby 125 forming a receptacle for surplus lead, means for closing the outer end of the bolt, and a cap connected with said outer end of the bolt for turning the latter.

2. In a pencil, a casing having a tip, an 130

elongated hollow nut longitudinally movable within said casing and fitting the interior walls of the same and guided by said walls, means for preventing the rotation of 5 said nut, a screw-threaded bolt rotatably mounted within and engaging said nut and also elongated, a plunger fixed to the inner end of said nut, said bolt projecting at its outer end beyond the outer end of the nut 10 and hollow throughout, being closed at all points except the outer end, thereby forming a receptacle for surplus lead or crayon, means for engaging the projecting outer end of the bolt to rotate the bolt and move the 15 nut longitudinally within the casing, said bolt and nut being removable from the casing in order to insert fresh lead or crayon into the pencil.

3. In a pencil, a casing having a tip provided with an elongated normally fixed passage adapted to support a lead, a rotatable bolt mounted centrally and symmetrically arranged within the end of the casing remote from the tip and extending inwardly 25 of the casing for a portion of its length, a nut inclosing said bolt and filling the space between the inner portion of the bolt and the casing, whereby lateral thrust upon the bolt is prevented and said nut is kept in 30 alinement, said nut being non-rotatably mounted within the casing and movable longitudinally thereof and extending around the inner end of the bolt, said bolt and nut having threaded engagement with 35 each other, whereby the latter can be moved longitudinally of the casing, and a plunger attached to the inner end of said nut, in alinement with said bolt and said passage and adapted to engage the inner end of the 40 lead.

4. A casing having a tip, an elongated hollow nut longitudinally movable within said casing and fitting the interior walls of the same and guided by said walls, means 45 for preventing the rotation of said nut, a plunger for feeding the lead or crayon connected to the inner end of said nut, a screw threaded hollow bolt rotatably mounted within and engaging said nut and also 50 elongated and projecting at its outer end beyond the outer end of the nut and also beyond the casing so that it may be operated to feed the nut toward the tip, said bolt being closed at its inner end and open at its 55 outer end and forming a receptacle for surplus lead or crayon, means for closing the outer end of the bolt, said bolt and nut with the plunger being removable from the casing to permit fresh lead or crayon to be inserted into the pencil.

5. In a pencil, a casing having a tip, an elongated hollow nut longitudinally movable within said casing and fitting the interior walls of the same and guided by said 60 walls, means for preventing the rotation of

said nut, a screw-threaded hollow bolt rotatably mounted within and engaging said nut and also elongated, a plunger fixed to the inner end of said nut, said bolt having a head projecting outside of the casing 70 beyond the nut, and having its inner end closed and its outer end open, a closure for said outer end, and a cap inclosing said head for actuating the bolt to feed the nut longitudinally, said bolt and nut being removable from the casing in order to insert fresh lead or crayon into the pencil.

6. In a pencil, a casing having a tip, a bearing removably fixed in the end of the casing remote from the tip and provided 80 with a flange extending outwardly over the end of the casing, a screw-threaded bolt rotatably mounted centrally within said bearing and provided with an enlarged head at one side thereof and with a ring on the 85 opposite side thereof to prevent axial movement of the bolt relatively to the bearing, a screw-threaded nut non-rotatably mounted within said casing and provided with interiorly arranged screw-threads in engagement with the screw-threads of the bolt whereby the rotation of the bolt advances the nut within the casing, and a plunger carried by said nut to advance the lead through said tip.

7. In a pencil, a casing having a tip, a bearing removably mounted in the end of said casing remote from the tip, a threaded bolt journaled in said bearing and projecting into said casing centrally thereof for a 100 portion of the length of the casing, a hollow elongated nut non-rotatably mounted within said casing, filling the space between the forward end of the bolt and the casing; extending around and across the end of said 105 bolt facing the tip to retain the bolt in alinement and provided with interior screw-threads in engagement with the screw-threads of the bolt, a plunger carried by said nut at its inner end and adapted to engage 110 the end of the lead to advance the lead through the tip, and means for preventing axial movement of said bolt in said bearing.

8. In a pencil, a casing having a normally fixed lead supporting tip, a bearing normally fixed in the end of the casing remote from the tip, a fixed guide coacting with the tip for directing the lead into the same and for clamping it, a screw-threaded bolt rotatably mounted within said bearing, provided with an enlarged head at one side thereof and with a ring on the opposite side thereof to prevent axial movement of the bolt relatively to the bearing and extending into said casing for a portion of the length 120 of the latter, a screw-threaded nut non-rotatably mounted within said casing to fill the same between the forward end of the bolt and the casing, inclosing said bolt to keep it in alinement, and provided with in- 125

teriorly arranged screw-threads in engagement with the screw-threads of said bolt, whereby the rotation of the bolt advances the nut within the casing, and a plunger 5 carried by said nut at its inner end to engage the end of the lead to advance the lead through said tip.

9. In a pencil, a casing having a tip, a screw-threaded bolt rotatably mounted within 10 in said casing, the interior of said bolt being provided with a chamber forming a magazine to receive surplus lead or crayon, a closure provided with an eraser for closing the end of said chamber and mounted 15 upon said bolt, a cap mounted upon the outer end of the bolt and adapted to perform the dual function of keeping the eraser clean and forming a finger hold to be grasped for rotating the bolt, and a nut having a plunger 20 and actuated by said bolt to force the lead through the tip.

10. In a pencil, a casing having a tip, a bearing at the end of the casing remote from the tip, a screw-threaded bolt engaging said 25 bearing and prevented from axial movement thereby, the interior of said bolt being provided with a chamber forming a magazine to receive surplus lead or crayon, a closure provided with an eraser for closing the end 30 of said chamber, a cap connected with the outer end of the bolt and adapted to perform the dual function of keeping the eraser clean and forming a finger hold to be grasped for rotating the bolt and a nut having a plunger 35 and actuated by said bolt to force lead through the tip.

11. In a pencil, a casing having a tip at one end, a bearing removably fixed in the end of the casing remote from said tip and provided 40 with an outwardly extending flange extending across the end of the casing, a screw-threaded bolt engaging said bearing and held from axial movement relatively to the bearing, a chamber in the interior of said 45 bolt adapted to receive surplus leads or crayons, a closure for said chamber, an eraser supported by said closure, an actuating cap mounted upon the head of said bolt and adapted to inclose said eraser and a nut 50 filling the space between the forward end of the bolt and the casing, having a plunger and actuated by said bolt to force the lead through the tip.

12. In a pencil, a casing having a tip provided with a passage centrally therethrough, said passage being roughened for a portion 55 of its length, a centering device mounted within the casing and having an inner funnel-shaped end bearing against the interior wall of the casing and an outer split end and a passage therethrough from one end to the other, which is alined with the passage 60 of the tip, the split end being adjustably mounted within the tip, the turning of which contracts or expands the split end

thereby providing a clutch for the lead intermediate of the length of the tip, a plunger arranged within the casing and movable longitudinally therein for advancing a lead through the centering device into the passage in the tip, and means acting upon the plunger to move the same. 70

13. In a pencil, a casing, a centering device at one end of the casing formed with an outwardly tapered passage therethrough, 75 said device having a split externally threaded outer end, a tip having a passage centrally therethrough and a threaded socket in its inner end for adjustably receiving the split externally threaded end of the said device 80 whereby the turning of the tip varies the cross section of the passage of the centering device, the said passage of the centering device being alined with the passage of the tip, the split end of the said device 85 serving as a clutch for the lead at a point intermediate of the length of the tip, a plunger coöoperating with said centering device and tip, and means for actuating the plunger. 90

14. In a pencil, a casing, a tip at one end of the casing having an elongated lead supporting passage, a centering device having a passage therethrough in alinement with the passage of the tip, said centering device and 95 tip being connected together in fixed relation, a plunger in alinement with said passages and of a length sufficient to pass through the passage of the centering device, a short lead holder mounted loosely on 100 the end of the plunger and adapted to support the lead during the initial movement of the plunger, said lead holder being carried by said initial movement of the plunger into contact with the centering device, 105 and when in engagement therewith the loose connection of the holder with the plunger allows the plunger to move through the holder and into the passage of the centering device to feed the lead through the tip, and 110 means located within the casing to feed the plunger forwardly.

15. In a pencil, a casing, a clamping member having a passage therethrough, mounted at one end of the casing and provided with 115 a funnel-shaped portion at its inner end, and an adjustable clamping portion at its outer end, a tip having an elongated lead supporting passage in alinement with said first-mentioned passage, mounted upon and 120 inclosing said clamping portion and adjustable thereon for varying the cross section of said first-mentioned passage, a plunger mounted within said casing and adapted to reciprocate in said passages, a lead holder 125 loosely encircling said plunger at one end movable thereon inwardly from the end and arranged to engage the funnel-shaped portion, and means for actuating said plunger. 130

16. In a pencil, a tip having a funnel-shaped centering device, a plunger having an enlarged portion at the end thereof adjacent the centering device, a holder provided with an axial opening receiving said plunger and adapted to engage the centering device, said axial opening being reduced at one end to retain the holder on said plunger, the opposite end of said opening being adapted to receive and directly engage the crayon or lead for directing the same through the tip, clamping portions on the centering device and coacting with the tip for gripping a lead passed into the tip, and means for actuating the plunger.
17. In a pencil, a casing having a tip, a nut movable longitudinally of said casing but non-rotatable relatively thereto, a plunger fixed to said nut, a screw-threaded bolt projecting into said nut for actuating the same, and a longitudinally extending slot through said casing whereby the distance between the end of the bolt and the head of the nut may be determined, said distance being the measure of the length of lead remaining in the tip.
18. In a pencil, a casing having a tip, a screw-threaded bolt rotatably mounted within said casing at the end thereof remote from the tip, a hollow and elongated nut non-rotatably mounted within the casing and provided with interior screw-threads in engagement with the screw-threads of the bolt, a plunger fixed to said nut, and longitudinally extending slots through the casing and nut whereby the distance between the end of the bolt and the head of nut may be determined, said distance being the measure of the length of lead remaining in the tip.
19. In a pencil, a casing, a clamping member at one end of said casing provided with a passage therethrough and having a funnel-shaped portion at its inner end and a slotted clamping portion at its outer end, said clamping portion being exteriorly threaded, a tip having a passage centrally therethrough and an interiorly threaded socket in its inner end receiving said slotted clamping portion for varying the cross section of
- the passage of the clamping member and 50 also providing a clutch at an intermediate point of the length of the tip, the passages of said clamping member and tip being aligned, said tip having its passage in advance of the clutch roughened to frictionally engage the lead, a plunger within said casing adapted to reciprocate in said passages, and means for actuating said plunger.
20. In a pencil, a casing comprising a tip having an elongated passage adapted to rigidly support a lead throughout its length, said passage being roughened to frictionally engage the lead and adjustable to clamp the lead, a screw-threaded bolt having a head rotatably mounted in the end of the casing 60 remote from the tip, projecting centrally into the same for a portion of the length thereof and arranged symmetrically relatively thereto, a hollow elongated nut encircling said bolt and filling the space between the same and said casing, said nut being movable longitudinally of the casing, but non-rotatable relatively thereto and extending around the inner end of the bolt, a plunger attached to said inner end of the 70 nut centrally thereof in alignment with said bolt and said passage and adapted to engage the inner end of the lead to advance the same through the passage, a centering device within the casing at one end of said plunger for 75 properly centering the lead into said passage from the rear and slots through said casing and nut exposing the bolt, whereby the length of lead remaining within the tip may be determined, said bolt comprising a magazine adapted to receive surplus leads, a stopper provided with an eraser for closing said magazine, and an actuating cap mounted upon the head of said bolt and inclosing said 85 eraser.
- 90 In testimony that I claim the foregoing as my own, I have hereto affixed my signature in the presence of two witnesses.
- WARREN STEPHEN WILLIAMS.
